UNITED STATES PATENT OFFICE.

EPPA H. RYON, OF WORCESTER, MASSACHUSETTS, ASSIGNOR TO CROMPTON & KNOWLES
LOOM WORKS, A CORPORATION OF MASSACHUSETTS.

WARPER.

1,061,012.

Specification of Letters Patent.

Patented May 6, 1913.

Application filed June 16, 1909. Serial No. 502,450.

To all whom it may concern:

Be it known that I, EPPA H. RYON, a citizen of the United States, residing at Worcester, in the county of Worcester and State 5 of Massachusetts, have invented certain new and useful Improvements in Warpers, of which the following is a specification.

My invention relates to a warper, and particularly to a creel warper, to wind the 10 warps from creels upon beams.

The object of my invention is to improve upon the construction of creel warpers as now ordinarily made, and more particularly to improve upon the drive mechanism, and 15 provide a pressure roll, in connection with the cone drive, to vary the speed of the warp beam, according to its diameter.

My invention consists in certain novel features of construction of my improvements as 20 will be hereinafter fully described.

I have only shown in the drawings parts of a creel warper with my improvements applied thereto, sufficient to enable those skilled in the art to understand the construction 25 and operation thereof.

Referring to the drawings:—Figure 1 is a front view of a creel warper embodying my improvements, with some of the parts broken out, and looking in the direction of arrow *a*, 30 Fig. 2. Fig. 2 is a vertical cross section, on line 2, 2, Fig. 1, looking in the direction of arrow *b*, same figure. Fig. 3 is a cross section, taken at a point indicated by line 3, 3, Fig. 1, looking in the direction of arrow *b*, 35 same figure, and shows the cone drive detached; some of the parts shown in Fig. 1 are not shown in this figure. Fig. 4 is a vertical cross section, on line 4, 4, Fig. 1, looking in the direction of arrow *d*, same 40 figure.

In the accompanying drawings, 1 is the left hand side frame of the warper, 2 is the right hand side frame, and 3, and 4 are two cross girths, and 2^a is a center girth. The left 45 hand side frame 1 is provided with a bearing 1', to loosely receive the hub 5' of the spur gear 5. The hub 5' has in this instance a bore for the gudgeon or journal of the warp beam. The gear 5 has in this instance 50 four spokes 5'', see Fig. 2. Two of the spokes 5'' are provided with elongated slots 5''' for a stud 6, which rotates the beam-head, not shown, at the left. The end frame 2 has a bracket 7 secured thereon with a

bearing 7', see Fig. 1, in which is adjustably 55 secured, by a set screw 8, a sleeve bearing 9 for the other gudgeon or journal of the warp beam 10. The warp beam 10, only one end of which is shown in Fig. 1, has in this instance a beam-head 11.

The warp 12, see Fig. 4, passes in this instance from the creel, not shown, through the dents of a stationary comb 13, over a roll 14, and around the tension roll 16, and over a second roll 15, then through a second 65 stationary comb 19, and over a roll 20 to the beam 10. The tension roll 16 is mounted in this instance on a shaft 17, which is provided with a brake or friction disk 18, in the usual way.

The pressure roll 21 extends longitudinally between the beam-heads, see Fig. 1, and is loosely held within recessed portions of heads 22' on two arms 22, which arms have hubs 22'', adjustably secured by set 75 screws 23 on a transverse shaft 24, see Fig. 4. The heads 22' carry rolls 22^a, mounted on pins 22^b, forming roller bearings for the pressure roll 21. One end of the shaft 24 has secured thereon an arm or lever 25, see 80 Figs. 1, and 4. The lever 25 carries a grooved roll or sheave 26, around which passes a rope or chain 27, one end of which is attached to a stationary part on the end frame 2. The rope or band 27 passes over 85 a second roll or sheave 28, see Fig. 1, and downwardly, and has attached to its end a weight bar 29, and weights 29', which act to force the roll 21 against the warp on the beam 10. The shaft 24 has also secured there- 90 on a second arm 30, see Fig. 4, the end of which is pivotally connected by a link 31, with a stud 32, which is adjustably secured in a slot in an arm 34, having its hub 34' loosely mounted on a stud 33. The arm 34 95 has the toothed segment 34'' thereon, which meshes with and is adapted to rotate a bevel pinion 35 connected with a sheave 36, which is loosely mounted on a stud 37' on a stand 37 on the side frame 2, see Fig. 4. A rope 100 or band 38 passes around the sheave 36, see Fig. 1, and also around sheaves 39 and 40, see Fig. 2. On the band 38 is secured a belt sliding fork 41, see Figs. 1 and 3, which is guided along a guide rod 105 42. A belt 43, which passes around the upper cone 44 and the lower cone 45, is carried toward the right in Fig. 1, by the fork

41, on the increasing of the diameter of the warp beam 10, as the warp 12 is wound thereon, to diminish the speed of the warp beam. The upper cone 44, which is mounted on a shaft 44', is driven by a pulley 46, also fast on said shaft 44', see Fig. 1.

47 is a loose pulley, to receive from the fast pulley 46, through the belt shipper 47', the belt, not shown, for driving the pulley 46.

15 The cone 45 to be driven, has its shaft 48 loosely mounted in bearings 49' on arms 49, see Figs. 2 and 3, which arms extend out from a sleeve 49'' mounted on a shaft 50 having bearings in stands 50' on the end frame 1 and center girth 2^a. The inner arm 49 is provided in this instance with a lug 49'', shown by broken lines in Fig. 3, through which extends a rod 51, which is 20 pivotally mounted at its lower end on a stud 52 on the center girth 2^a, and has its upper end threaded to receive a nut wheel 53, which is turned in one direction or the other, as desired, to raise or lower the arms 49, to loosen or tighten the belt 43 connecting the cones 44 and 45. The shaft 48 has mounted on its outer end a pinion, not shown, which meshes with and drives a gear 54, see Fig. 2, loosely mounted on the shaft 50. Connected with the gear 54 is a pinion 30 55 which meshes with and drives the gear 5.

Some parts are shown in the drawings, and are lettered therein, which are not particularly described herein, as they are not 35 claimed as a part of my improvements in

warpers particularly shown and described herein.

It will be understood that the details of construction of my improvements may be varied if desired.

Having thus described my invention, what I claim as new and desire to secure by Letters Patent is;—

1. In a warper, a pressure roll for the yarn on the beam being wound, pivotally mounted arms to coöperate with said pressure roll, manually controlled means to vary the pressure on said roll, a pair of cones, a driving belt connecting said cones, and connections from said pressure roll to said belt, 45 said connections including a pivotally mounted segment arm having teeth thereon, a pinion to mesh with said teeth, and having a drum fast thereto, a second rotatable drum, a cord passing around said drums and 50 connected to said belt.

2. In a warper, a beam upon which the warp is wound, a pressure roll to bear against the yarn on said beam, means to vary the pressure of said roll, a pair of 60 cones, a driving belt connecting said cones, and connections from said pressure roll to said belt, said connections including a segment arm; a pinion, two drums, and a flexible connection between said drums and said 65 belt.

EPPA H. RYON.
